UNITED STATES PATENT OFFICE.

GEORGE B. MOULTON, OF BAKER CITY, OREGON.

DESIGN FOR A STIRRUP.

SPECIFICATION forming part of Design No. 20,746, dated May 19, 1891.

Application filed April 8, 1891. Serial No. 388,192. Term of patent 7 years.

To all whom it may concern:

Be it known that I, GEORGE B. MOULTON, a citizen of the United States, residing at Baker City, in the county of Baker and State of Oregon, have invented and produced a new and original Design for a Stirrup, of which the following is a specification, reference being had to the accompanying drawings, forming part thereof.

Figure 1 represents a front view of a stirrup, showing my design, and Fig. 2 a side view of the same, these two views being deemed necessary to fully illustrate my design.

A A indicate the sides of the stirrup, which, as seen from the front, are mainly of arched or reversely-bowed form relatively to each other at their upper portions a a, with lower continuations b b, of straight and parallel shape relatively to each other, each of said 20 sides terminating above in a figure resem-

bling in the main a bevel-backed button c, having the figure of a circular hole or space d in its center, and each of said sides terminating below in a figure e, of approximately circular form, with an inner space-like figure f, of annular shape, having a salient ring-like figure g within it, and still another inner or central figure h, of stud form, as clearly shown in Fig. 2. The roll B of the stirrup is of cylindrical contour, and the foot-rest C of the 30 stirrup of flattened concave shape in direction of its length, with rounded upper ends i, as seen from the side, as represented in Fig. 2.

I claim—

The design for a stirrup herein shown and 35 described.

GEORGE B. MOULTON.
